CLAIM

We claim the ornamental design for a large volume pump, as shown and described.

DESCRIPTION

FIG. 1 is a perspective view of a large volume pump. FIG. 2 is a front elevation view of the large volume pump. FIG. 3 is a rear elevation view of the large volume pump. FIG. 4 is a side elevation view of the large volume pump. FIG. 5 is another side elevation view of the large volume pump, from the side opposite that in FIG. 4. FIG. 6 is a top plan view of the large volume pump; and, FIG. 7 is a bottom plan view of the large volume pump.

(Continued)

The dashed broken lines depict portions of the large volume pump that form no part of the claimed design.
